(57) **CLAIM**

The ornamental design for a monitor, as shown and described.

DESCRIPTION

FIG. 1 is a left side view of a monitor shown in a closed, slightly offset configuration;
FIG. 2 is a back view thereof;
FIG. 3 is a right side view thereof;
FIG. 4 is a perspective back view thereof;
FIG. 5 is a top view thereof;
FIG. 6 is a front perspective view thereof;
FIG. 7 is a bottom view thereof;
FIG. 8 is a left side view of the monitor shown in a closed configuration;
FIG. 9 is a back view thereof;
FIG. 10 is a right side view thereof;
FIG. 11 is a back perspective view thereof;
FIG. 12 is a top view thereof;
FIG. 13 is a top perspective view thereof;
FIG. 14 is a bottom view thereof;
FIG. 15 is a back view of the monitor shown in an open configuration;
FIG. 16 is a left side view thereof;
FIG. 17 is a right side view thereof;
FIG. 18 is a back perspective view thereof;
FIG. 19 is a top view thereof;
FIG. 20 is a front perspective view thereof;
FIG. 21 is a bottom view thereof;
FIG. 22 is a front view thereof;
FIG. 23 is a back view of the monitor shown in an open pivoted configuration;
FIG. 24 is a left side view thereof;
FIG. 25 is a right side view thereof;
FIG. 26 is a back perspective view thereof;
FIG. 27 is a top view thereof;
FIG. 28 is a front perspective view thereof;
FIG. 29 is a bottom view thereof;
FIG. 30 is a front view thereof; and,
FIG. 31 is an enlarged view of the portion indicated in FIG. 1.

The rectangle shown in broken lines in FIG. 1 indicates the location of the enlarged view shown in FIG. 31 and forms no part of the claimed design. All other broken lines show portions of the monitor that form no part of the claimed design.

1 Claim, 31 Drawing Sheets
